CLAIM

The ornamental design for an implement for exercise rack, as shown and described.

DESCRIPTION

FIG. 1 is a top, front, left perspective view of an implement for exercise rack showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, right perspective view thereof.

The broken lines immediately adjacent to the shaded areas define the bounds of the claimed design and form no part thereof. The broken lines depicting the remainder of the implement for exercise rack show portions that form no part of the claimed design. The broken lines depicting the exercise rack are for the purpose of illustrating environmental structure, which form no part of the claimed design.
